UNITED STATES PATENT OFFICE.

WILLIAM RESOR, OF CINCINNATI, OHIO.

HEATING-STOVES.

Specification forming part of Letters Patent No. 58,477, dated October 2, 1866.

To all whom it may concern:

Be it known that I, WILLIAM RESOR, of Cincinnati, Hamilton county, Ohio, have invented a new and useful Heating-Stove; and I do hereby declare the following to be a full, clear, and exact description thereof, reference being had to the accompanying drawings, making part of this specification.

My invention relates to the class of wood-burning stoves for heating purposes in which the smoke is conducted down the front, thence rearward beneath the fire-bed, and thence upward to the escape-pipe; and the object of the present improvement is to combine, with the advantages of compact and sightly construction, an effective and manageable application of the draft-air, and an adequate extent of heating-surfaces.

In the accompanying drawings, Figure 1 is an axially-divided perspective view of a stove embodying my improvements. Fig. 2 is a horizontal section at the line *x x*, Fig. 1.

The bottom A and the top B may consist of oval plates of cast-iron, while the body C may consist of a single piece of sheet-iron bent into the form desired.

A partition, D, which rises vertically from the bottom plate, about two-thirds of the height of the fire-chamber, forms, in conjunction with the adjacent portion of the body-plate, a descending flue, E, which discharges into a flue, F, extending rearward under the fire-bed, and terminating in a neck, G, for the reception of an external ascending flue, H, whose upper end is secured in a collar, J, on the under side of the top plate, the upper side of which has the customary neck, I, for the escape-pipe.

The body-plate, a little above the fire-bed and directly opposite the descending flue, is perforated with draft-apertures K, which are closed or opened at will by means of a register, L.

M is a door for insertion of the fuel. N is a damper which, being opened, permits the direct escape of the smoke into the chimney.

The top plate may be perforated at O, as shown, to receive any boiling or heating vessel. P is an ash-door.

This invention is believed to combine more completely than heretofore some important desiderata of a wood-burning stove. Its oval form, prolonged flue or smoke-passage, and external exit-pipe, while preventing a too rapid combustion, retain the heat in the stove, afford a large area of heating and radiating surfaces, and permit the use of long cord-wood without unsightly bulk.

The draft-air, entering the stove on the side diametrically opposite the descending flue, and as much below the mid-height thereof as the entrance of said flue is above it, is compelled before escaping, to pass entirely across the main body of the fire-chamber.

I claim herein as new and of my invention—

The arrangement of oval fire-chamber A B C, interior descending flue, E, bottom flue, F, neck G, external ascending flue, H, collar J, and registered draft-inlet K L, substantially as and for the purpose set forth.

In testimony of which invention I hereunto set my hand.

WM. RESOR.
